UNITED STATES PATENT OFFICE.

WILLIAM R. HURSEY, OF BIRMINGHAM, ALABAMA.

FLUSH-VALVE.

1,314,873.

Specification of Letters Patent. Patented Sept. 2, 1919.

Application filed February 23, 1917, Serial No. 150,427. Renewed February 7, 1919. Serial No. 275,679.

To all whom it may concern:

Be it known that I, WILLIAM R. HURSEY, a citizen of the United States, residing at Birmingham, in the county of Jefferson and 5 State of Alabama, have invented certain new and useful Improvements in Flush-Valves, of which the following is a specification.

My invention relates to flush tank apparatus, and the principal objects of the invention are to provide means for locking the float in its raised position, for locking the outlet valve in its raised position during the descent of the float, and for automatically opening said outlet valve in case 15 the water level in the tank rises above a pre-determined point.

A further object of the invention is to produce the above results by mechanism which is exceedingly simple and compact in its 20 construction, and which is not likely to get out of order.

A still further object is to provide flush tank apparatus in which the necessity for the employment of the usual hollow rubber 25 ball for the outlet valve is avoided, and in which a solid valve of greater specific gravity than water can be substituted.

In order that the invention may be readily understood, reference is had to the accompanying drawings, forming a part of 30 this specification, and in which,

Figure 1 is a vertical section through a flush tank showing my improved valve mechanism therein, the operative parts being shown in elevation;

Fig. 2 is an enlarged side elevation of my improved valve mechanism, parts being in section, and other parts being broken away. In this figure the parts are shown in 40 normal position;

Fig. 3 is a view similar to Fig. 2, showing the position which the parts assume when the water reaches an abnormal level;

Fig. 4 is a similar view, illustrating the 45 position of the parts during the flushing operation;

Fig. 5 is a similar view, showing the position of the parts at the end of the flushing operation and when refilling of the tank begins;

Fig. 6 is an inverted plan view of the inlet valve; and,

Fig. 7 is a transverse section on the line 7—7 of Fig. 2, looking in the direction of the 50 arrow.

Referring to the drawings in detail, X designates a tank; which may be of any suitable construction, and in which is located the usual float A. This float is operatively connected with the valve mechanism designated 60 in its entirety by the reference character B and controlling the flow of water from the inlet pipe C, and its discharge from the outlet D. The tank is operated by any suitable lever F, connected with the outlet valve 65 lever by means of a chain E.

My improved valve operating mechanism comprises a supporting bracket having a base 1, secured to the bottom of the tank, and spaced parallel side members 2, as 70 clearly shown in Fig. 7. The inlet valve is of the shape shown in Fig. 6, and comprises a central portion or valve proper 3, which may be lined with a suitable soft material and which is adapted to fit down over the 75 upper end of the inlet pipe C. At one side of the valve 3 projects a bifurcated portion 4, which is pivoted to a pin 5, secured to the frame members 2. The other end of the valve member terminates in a pair of spaced 80 arms 6—6^a, as clearly shown in the drawing and as hereinafter more fully referred to.

The float A is secured to a float-operated lever 7, having at its lower end a body portion or blade 8, pivoted at 9 to a pin which 85 is supported in the frame 2. In the lower part of the body 8 is secured a pin 10, which extends between the arms 6—6^a of the inlet valve and serves to operate this valve as the float rises and falls, as will be evident. The 90 upper edge of the body 8 has at its forward corner a toe 11, which is adapted to engage a hook 12, the rear portion 13 of which is pivoted on the pin 5 between the bifurcated end 4 of the inlet valve. This hook is 95 freely movable and operates under the influence of gravity. The body 8 also has a heel 14, the purpose of which will be hereinafter more fully described.

Also pivoted to the pin 9 alongside of the 100 lever 7 is the outlet valve lever 15, carrying at its end the outlet valve 16, secured to the lever in any suitable way, as by means of a bolt and nut 17. The valve 16 preferably consists of a disk of some heavy material, 105 such as lead, and may, if desired, be provided with a facing 18 of soft rubber, or the like. This valve seats upon the flange 19 of the outlet pipe D and forms therewith a watertight joint.

The rear end of lever 15 also is provided with a blade or body portion 20, disposed close to and parallel with the blade 8 of lever 7, both of these blades and levers being mounted between the side members 2 of the supporting frame. The blade 20 is cut away to form a sector-shaped opening, as clearly shown in the drawings, through which opening the pin 10 projects. Under certain circumstances, the pin 10 is adapted to engage one side 21 of the sector-shaped opening, as shown in Fig. 3.

The blade 20 has at its upper edge a nose 22, adapted to engage and be engaged by the hook 12.

The mechanism will best be understood from a description of its operation, which is as follows:

When the tank is full up to its normal level, as shown in Figs. 1 and 2, the float causes the pin 10 to bear upon the arm 6 of the inlet valve and thus hold the inlet closed. The float is locked in its normal upper position by means of the toe 11 engaging the shoulder 12 of the hook, as clearly shown in Fig. 2. In this connection, it will be observed that the toe 11 projects slightly above the nose 22, in order that the engagement just described may take place, since, as shown in this figure, the hook rests upon and is supported by the nose 22. This locking of the float in its normal upper position prevents accidental flushing of the tank and wasting of water in case the float should leak and fill with water.

If on account of leakage of the inlet valve, or for any other reason, the water level in the tank should rise abnormally high, the float lever 7 will be elevated to the position shown in Fig. 3. In moving to this position, the pin 10 engages the edge 21 of the sector in the blade 20, and thus slightly rotates the outlet valve lever in an upward direction, thereby imparting an initial opening movement to the outlet valve 16. In other words, this valve is slightly elevated from its seat, or cracked. This slight opening of the outlet valve permits the water to escape until the normal level has been restored, whereupon the outlet valve closes. This arrangement avoids the necessity for providing an independent outlet or overflow to take care of excess water.

When it is desired to flush the tank, the outlet valve is lifted as by means of the chain E and lever F until the valve lever 15 assumes the position shown in Fig. 4. In moving to this position from that shown in Fig. 2, the nose 22 has lifted the hook 12 and tripped it out of engagement with the toe 11 of the float lever, thus permitting the float to move downward as the water escapes. After releasing the float lever as described, the nose 22 then engages under the hook 12, as shown in Fig. 4, and the outlet

valve is thus locked in raised position during the time that the flushing operation is taking place.

When all the water has run out of the tank and the float and lever 7 have fallen to the position indicated in Fig. 5, the heel 14 of the float lever engages under the hook 12 and lifts it so that the nose 22 of the outlet valve lever is released and the outlet valve drops into position over the outlet, as shown in Fig. 5.

From the above, it will be seen that the hook 12 is adapted to engage both the levers 7 and 15 but that it can engage only one of these levers at a time. This is due to the fact that when one lever moves into locking position it releases the other. In other words, the hook serves to lock both the float lever and the outlet valve lever in their raised positions but it can only do so at different times. Also the movement of the float to its lowermost position serves to release the outlet valve and restore it to normal position. When the float rises to its normal position, it engages the hook 12 and is locked in such position.

It will be observed that the outlet valve 16 operates by gravity and does not float on the water as is the case with many outlet valves heretofore employed. The valve being solid, as described, is not subject to the rapid deterioration which has proven so objectionable with the hollow valves heretofore employed. The valve 16 is preferably not rigid with the lever 15, but is loosely secured thereto, whereby such valve has sufficient freedom of movement to allow it to adjust itself snugly on the valve seat.

What I claim is:

1. In a flush tank apparatus, a float operated lever and an outlet valve lever pivoted about a common center, and a hook actuated by one lever and serving to control the other.

2. In a flush tank apparatus, a float operated lever and an outlet valve lever disposed side by side, a common hook arranged to engage and hold both of said levers, and means carried by each lever for operating said hook to release the other lever.

3. In a flush tank apparatus, a float, an inlet valve, a lever carrying said float and operatively connected with said inlet valve, a hook adapted to hold said float in raised position, and an outlet valve lever having a member adapted when raised, to engage said hook to trip said float lever, and to be engaged by said hook to maintain itself in raised position.

4. In a device of the character described, the combination with an outlet valve lever and a float operated lever mounted side by side, a single hook adapted to engage both of said levers and hold them in raised position, and means compelling said hook to release one lever before engaging the other,

whereby only one lever can be held at a time.

5. In a device of the character described, the combination with an outlet valve lever and a float operated lever mounted side by side, a single hook adapted to engage both of said levers and hold them in raised position, and means for causing said hook to release said float lever before engaging said outlet valve lever.

6. In a device of the character described, an outlet valve lever and a float operated lever pivotally mounted side by side on a common center, a hook adapted to engage 15 said outlet valve lever to hold it in its raised position, and said float lever having a heel arranged to trip said hook out of engagement with said outlet valve lever when the float approaches its lower position.

20 7. In a device of the character described, an outlet valve lever and a float operated lever pivotally mounted side by side on a common center, a hook adapted to engage said float lever to hold it in its raised position, and said outlet valve lever having 25 a nose arranged to trip said hook out of engagement with said float lever when said outlet valve is moved to open position.

8. In a flush tank apparatus, an outlet 30 valve lever and a float operated lever pivotally mounted side by side, and a connection

between said levers permitting independent movement thereof within normal limits, said connection serving to cause said levers to move together when the float lever rises 35 above its normal position.

9. In a flush tank apparatus, a float operated lever and an outlet valve lever independently pivoted about a common center, and connections between said levers whereby 40 movement of the float operated lever to abnormal position serves to shift the outlet valve lever in the opening direction.

10. In a flush tank apparatus, the combination with an inlet valve and outlet valve, 45 a lever to which said outlet valve is attached, a float lever, said levers being pivoted about a common center, a pin carried by said float lever and operatively connected with said inlet valve, said outlet valve 50 lever having a slot in which said pin engages, said pin and slot being so related as to permit independent movement of said levers during the normal operation of the apparatus but serving to impart an initial 55 opening movement to the outlet valve when the float lever rises beyond a pre-determined position.

In testimony whereof I have affixed my signature.

WILLIAM R. HURSEY.
